FIG. 1 is a perspective view of a nursing bottle showing my new design;

FIG. 2 is a front view of the nursing bottle of FIG. 1, the rear view being a mirror image thereof;

FIG. 3 is side view of the nursing bottle of FIG. 1, the opposite side being a mirror image thereof;

FIG. 4 is a top view of the nursing bottle of FIG. 1;

FIG. 5 is a perspective view of a second embodiment of a nursing bottle showing my new design;

FIG. 6 is a front view of the nursing bottle of FIG. 5, the rear view being a mirror image thereof;

FIG. 7 is a side view of the nursing bottle of FIG. 5, the opposite side being a mirror image thereof; and,

FIG. 8 is a top view of the nursing bottle of FIG. 5.

The broken line showing in FIGS. 1 through 8 is for illustrative purposes only and forms no part of the claimed design.
